UNITED STATES PATENT OFFICE.

PAUL KUGEL AND VICTOR GELPK, OF ZÜRICH, SWITZERLAND.

CENTRIFUGAL HIGH-PRESSURE PUMP.

SPECIFICATION forming part of Letters Patent No. 743,296, dated November 3, 1903.

Application filed March 30, 1903. Serial No. 150,231. (No model.)

To all whom it may concern:

Be it known that we, PAUL KUGEL and VICTOR GELPK, engineers, citizens of the Republic of Switzerland, and residents of Zürich, Switzerland, have invented new and useful Improvements in Centrifugal High-Pressure Pumps, of which the following is a specification.

For the realization of a high degree of utility in centrifugal pumps and turbines the following points are necessary: first, the regular course of the velocity of the moving liquid conforms to size and direction for the working wheel as well as for the guide-wheel; second, the slowest possible change of the velocity of the flowing liquid according to size and direction, and third, the smallest possible loss owing to space or passage between the working and guide wheels. The centrifugal high-pressure pump forming the subject of the present application fulfils all these conditions.

The invention is illustrated in the accompanying drawings, in which—

Figure 1 represents a central vertical section of a high-pressure pump of different steps; Fig. 2, a cross-section on line A B of Fig. 1; Fig. 3, a section through one guide and one working wheel on a larger scale; Fig. 4, a section on line C D E of Fig. 3; Fig. 5, a section on line F G H of Fig. 3; Figs. 6 and 7, an arrangement of wheels with intermittent blades or vanes. Figs. 8 and 9 show further forms of blades or vanes.

The pump consists of a number of guide-wheels *b d f h* and *b' d' f' h'*, respectively, and a number of working wheels *c e g i* and *c' e' g' i'*, respectively. Each guide-wheel except the first, *b b'*, as well as each working wheel except the last, *i i'*, contains a canal of the shape of an **S**, which is destined to the reception of guide-wheel blades or vanes.

The following is the mode of operation: The liquid flows in an axial direction against the working wheel *c* and *c'*, takes part through these vanes in the rotating movement, and derives therefrom a pressure which is nearly equal to the difference of the centrifugal power outside and inside. The liquid leaves the blades or vanes of the working wheel in an axial movement in order to run over in an axial direction on the guide-wheel vanes. These guide-wheel vanes turn the direction

and the velocity of the promoting liquid in such a regular way as is necessary for the entrance in the next working wheel *e* and *e'*, &c. 55

The fulfilling of foregoing conditions for the good effect of the machine necessitates, first, that the regular course of the current conforms to the size and direction. From Figs. 3 to 5 can be seen that the working and guide wheel vanes extend through the whole **S**-like channel. The changes in velocity in the several channel-cuts take place, therefore, in a steady way and without shock to the moving liquid. At the same time is prevented the rise 65 of whirlpools and ensuing loss of work. This idea of continued vanes does not suffer from the fact that they are interrupted on a short space, the interruption being such that a continuance of the direction of the current is kept 70 on. It is unimportant for the mode of operation of the machine whether the blades are placed at the entrance or exit in straight lines vertically, Fig. 6, or slanting toward the axis, Fig. 8, or end in sweeping curves, 75 Fig. 9, as long as the continuation of the conduct is assured. Conforming to condition 2, a very slow shifting of the velocity of the promoting liquid is insured by spreading the vanes over the entire length of the channel, 80 and therefore a minimum of high-pressure loss, which shows always by varying velocity. The curve is also very smooth, owing to the vanes being elongated, and the high-pressure loss is therefrom very small, which would be 85 greater if short and therefore sharply-curved blades were used. From Figs. 1 to 3 may be further seen that owing to the chosen **S** form of the channel the curve radius at the passage from working wheel into guide-wheel 90 and back is bigger than any other construction with exit vertical with the axis. Consequently there is in this invention a much smaller loss of high pressure through the curve, as is the case with centrifugal pumps 95 having a radial exit.

Through this invention the loss of work through the space between working parts is produced, an exit of the promoting liquid being hindered through a single or repeated 100 cylindrical twisting in of the working and guide wheel against each other. It is immaterial for these twistings whether the separation of the working or guide wheels falls ac-

curately in a plane vertical with the axis or in a conical plane whose generatrix is only little inclined toward foregoing plane. The use of the working wheels as balance-pistons 5 comes of itself by this method of calking, as otherwise the pressure liquid introduced from outside could not enter into the channels of the working wheels.

As in the present construction the passage 10 of the promoting liquid from working into guide-wheel happens in the direction of the axis, the diameter of the pressure-giving working wheel is nearly equal to the diameter of the covering-case. In consequence the 15 pressure given to the promoting liquid through the function of the centrifugal power goes up to a maximum, and it is greater than on any other construction having no axial passage at equal conditions. Therein lies the 20 great advantage that present invention can always be constructed smaller and lighter than any other centrifugal pump with radial exit at equal conditions. The combination of

all points conducting to the fulfilling of above conditions assure to this machine great 25 utility by simplest operation. The same advantage accrues also to the machine when used as an air-forcing device.

We claim—

A centrifugal pump comprising a casing, a 30 shaft, guide-wheels secured to the casing, working wheels on the shaft, the said guide-wheels and the said working wheels each having approximately S-shaped channels with vanes therein, the inlets and outlets from 35 said channels being parallel with the axis of the shaft, substantially as described.

In testimony whereof we have hereunto set our hands in presence of two subscribing witnesses.

PAUL KUGEL.
VICTOR GELPK.
